(57) **CLAIM**

The ornamental design for a strap for an orthopedic device, as shown and described.

DESCRIPTION

This application incorporates by reference U.S. patent application Ser. No. 15/672,593, filed on Aug. 9, 2017.

FIG. 1 is a perspective view of a strap for an orthopedic device.

FIG. 2 is a top plan view according to the strap for an orthopedic device of FIG. 1.

FIG. 3 is a bottom plan view according to the strap for an orthopedic device of FIG. 1.

FIG. 4 is a first side elevational view according to the strap for an orthopedic device of FIG. 1.

FIG. 5 is a second side elevational view according to the strap for an orthopedic device of FIG. 1.

FIG. 6 is a front elevational view according to the strap for an orthopedic device of FIG. 1; and,

FIG. 7 is a rear elevational view according to the strap for an orthopedic device of FIG. 1.

1 Claim, 3 Drawing Sheets
